REVERSIBLE BRUSH

Samuel W. Hall, Chicago, Ill., assignor of one-third to The Wooster Brush Company, Wooster, Ohio

Application July 28, 1932, Serial No. 625,460

2 Claims. (Cl. 15—176)

My invention relates to new and useful improvements in brushes and more particularly to what might be termed a reversible brush primarily intended for applying posters, paint, whitewash or the like, or for use by paper hangers for applying paste, although it will be appreciated that such a brush may be used for various other purposes.

The principal object of the present invention resides in the provision of a brush having a head portion or member to which a handle may be attached and a readily removable and reversible bristle carrying portion or member adapted to be connected to the head portion.

15 A further object consists in the provision of novel means whereby the bristle carrying portion or member may be connected to or removed from the head portion by a sliding movement of one relative to the other and means for securing the 20 two portions or members against said sliding movement and in operable relation.

With the above and other objects in view, which will appear as the description proceeds, my invention consists in the novel details of construction, and arrangement of parts, described in 25 the following specification and illustrated in the accompanying drawings, and while I have illustrated and described the preferred embodiments of the invention, as they now appear to me, it 30 will be understood that such changes may be made as will fall within the scope of the appended claims.

In the drawing:—

Fig. 1 is a side elevation with parts broken 35 away.

Fig. 2 is a vertical section on the line 2—2 of Fig. 1 looking in the direction of the arrows; and

Fig. 3 is a bottom plan of the head portion or member.

40 In the drawing A denotes generally the head portion or member and B the bristle carrying portion or member. The head portion is of relatively elongated shape, as shown more particularly in Figs. 1 and 2 of the drawing, and is provided 45 with the diagonally extending opening 1 in which the end of the handle 2 is inserted. An elongated recess 3 is formed in the lower or bottom edge of the head portion A and extending over this recess is a plate 4 secured to the head by means 50 of the screws 5 or other suitable fastening means. The plate is provided centrally with the threaded opening 6 and on opposite sides of this opening are the slots 7 terminating at the ends in enlarged openings designated 8. As shown more particularly in Figs. 1 and 2 of the drawings the plate 55

4 is of such a length and width as to extend beyond the ends and side edges of the recess 3 and the inner face of the plate will be spaced from the inner surface of the recess for a purpose which will be later apparent.

5 The bristle carrying portion or member B includes an elongated block 9 around which the bristles 10 are positioned and secured in place by means of the band or strip 11 attached to the block by means of the nails 12 or other suitable 10 fastenings. As shown more particularly in Fig. 2 of the drawing the block 9 is flanged at its upper end as shown at 13 to engage the bottom surface of the head portion or member A and the block 9 is of a length equal to the length 15 of the head A with the flanges 13 extended to a width corresponding to the width of the lower surface of the head. Threaded through the block 9 are the bolts 14 provided at their upper ends with the heads 15 and secured in proper 20 position, by means of the nuts 16. As shown more particularly in Fig. 1 of the drawing the heads 15 of the bolts 14 are positioned above the upper surface of the block 9 a sufficient distance 25 that the bolts 14 extend through the slots 7 in the plate 4 with the lower faces of the heads engaging the upper surface of the plate. The block 9 is secured to the head A, against sliding movement, by means of the screw 17, this screw extending through the block 9 and threaded into 30 the opening 6 of the plate 4.

In brushes of the character adapted for use in applying posters, paint, whitewash, paste or the like, where the handle is connected to the brush at an angle one edge of the brush wears away 35 much quicker than the opposite edge and thereby the life of the brush is ordinary lessened. To overcome this I have provided the brush having the reversible bristle carrying portion or member and if the bristle carrying portion or member is 40 reversed at suitable intervals the bristles will wear evenly and the life of the brush will be extended. Normally when ready for use the bristle carrying portion or member B is connected to the head portion or member A, as shown more particularly 45 in Fig. 1 of the drawing. When it is desired to reverse the bristle carrying portion the screw 17 is turned to remove the end thereof from the threaded opening 6 in the plate 4 and when this has been done the block 9, with the bristles 10 50 may be slid in either direction relative to the head A to position the heads 15 of the bolts 14 in alignment with the enlarged ends 8 of the slots 7. When in this position the heads 15 of the bolts 14 may be withdrawn through the en- 55

larged portions 8 and the bristle carrying portion or member reversed as an entirety. When reversed the heads 15 of the bolts 14 will be reinserted through the enlarged portions 8 of the 5 slots 7 and the bristle carrying portion B slid relative to the head portion A to position the heads 15 of the bolts 14 intermediate the enlargements 8 of the slots 7 with the heads overlying and engaging the upper surface of the plate 4, as 10 shown more particularly in Fig. 1 and the heads positioned in the recess 3. When thus positioned the screw 17 is rethreaded into the opening 6 and the members A and B are held against relative 15 sliding movement. It will thus be seen that I have provided novel means whereby the bristle carrying member of a brush may be readily connected to or disconnected from the head portion to which the handle is connected and that such bristle carrying portion or member may be easily 20 reversed in order to prolong the life of the brush.

Having fully described my invention what I claim as new and desire to secure by Letters Patent is:—

1. A brush including a head portion having an 25 elongated recess formed in its bottom edge intermediate the ends thereof and a plate covering the recess, the plate having a slot terminating in an enlargement at one end, a bristle carrying portion adapted to be readily attached to and detachable from and reversible relative to the head portion, said bristle carrying portion having a 30 face portion engageable with the bottom edge of the head portion and plate carried thereby, and

a headed member adapted to be passed through the enlarged end of the slot in the plate, into the recess in the bottom edge of the head portion and moved into the slot by sliding movement of the bristle carrying portion relative to the head portion, and means engageable through the bristle carrying portion and engageable with the plate carried by the head portion for preventing sliding movement of the bristle carrying portion relative to the head portion. 5

2. A brush including a head portion having an elongated recess formed in its bottom edge intermediate the ends thereof and a plate countersunk in the bottom edge and covering the recess, the plate having a slot terminating in an enlargement at one end, a bristle carrying portion adapted to be readily attached to and detachable from and reversible relative to the head portion, said bristle carrying portion having a face portion engageable with the bottom edge of the head portion and plate carried thereby, and a headed member adapted to be passed through the enlarged end of the slot in the plate, into the recess in the bottom edge of the head portion and moved into the slot by sliding movement of the bristle carrying portion relative to the head portion, and means engageable through the bristle carrying portion and engageable with the plate carried by the head portion for preventing sliding movement of the bristle carrying portion relative to the head portion. 10 15 20 25 30
